SPARK GAP ELECTRICAL APPARATUS

Michael Edward Haine, John Millar Meek, and
John Drummond Craggs, Sale, England, as-
signors to Metropolitan-Vickers Electrical Com-
pany Limited, London, England, a company of
Great Britain

Application March 23, 1945, Serial No. 584,304
In Great Britain June 21, 1943

Section 1, Public Law 690, August 8, 1946
Patent expires June 21, 1963

3 Claims. (Cl. 250—27.5)

1

This invention relates to spark gap electrical apparatus, and comprises an improvement in or modification of the arrangements disclosed in Patent No. 2,400,456, granted May 14, 1946, and in application Ser. No. 514,865, filed December 18, 1943.

The said patent and application relate to a tripable spark gap device of the kind comprising input and output main electrodes fixed apart appreciably beyond their normal sparkover spacing in relation to a predetermined voltage to be normally applied across the gap, a fixed trigger electrode associated with one of said main electrodes, an envelope enclosing said electrodes and at least one inert gas mixed with a small proportion of a quenching gas filling said envelope at a pressure above atmosphere, said trigger electrode being formed with a relatively small radius of curvature at the arcing tip and the main electrode associated with the trigger electrode being apertured and the tip of the trigger electrode protruding into the neighborhood of the aperture and being spaced from the sides of the aperture a distance such as to ensure a breakdown when a triggering pulse is applied to the trigger electrode.

The main object of the present invention is to improve the reliability of operation of such a device and ensure that breakdown shall always occur when a trigger voltage of predetermined value is applied.

According to the present invention, an insulating tube of appreciable specific inductive capacity and with a relatively thick wall encircles said trigger electrode over an appreciable portion of its length and is internally spaced from said trigger electrode by a relatively small amount to form an annular gap, and an electrical conductor is located externally of the insulating tube and is electrically connected to said apertured electrode, the arrangement being such that when a triggering pulse is applied between the electrical conductor and the trigger electrode an intense electric stress is set up in said annular gap producing corona discharge.

In the drawing—

Fig. 1 is a detail sectional view of the electrodes of the improved spark gap electrical apparatus.

Fig. 2 is a view partly in elevation and partly in section, of the envelope and the electrodes mounted therein and which envelope encloses the gas surrounding the electrodes.

Referring to Fig. 1 of the accompanying drawing, which shows a modification of the form shown in the aforesaid application and patent,

2

at 101 is shown the anode which comprises the spherical end portion only: it is supported by the posts 102 which are butt-welded to the tungsten leads 103 sealed through the glass foot 104 of the main bulb. The trigger wire is shown at 105. At 106 is shown the insulating tube which in this case is shown as a glass "bead" which at its left-hand end is fixed by fusion to the glass foot 104. This glass bead has an axial hole providing, as shown, a distinct clearance with respect to the trigger wire 105 passing through it. It is in this appreciable annular gap that, due to the higher electrical stress, the corona is set up requisite for irradiating the main spark gap. 10 This is due to the high electrical stress set up in the annular gap as a result of the insulating tube which, due to its high specific inductive capacity, concentrates the voltage gradient in the gap. To enhance this effect the bead, in the figure, is of 15 considerable thickness compared with that shown in Fig. 5 of the drawings accompanying the aforesaid specification, and is closely surrounded by the nickel or other metal sleeve 107 which does not extend to the right-hand end of 20 the glass insulating bead 106. The sleeve 107 is connected to the anode support 102 by a wire or strip 108. In the alternative equivalent arrangement (not shown) the glass insulator 106 is replaced by a material having an appreciably 25 higher dielectric constant than glass, such as "Rutile," or a rutile material known in the trade as "Faradex." In such case the metal sleeve 107 can be omitted as the triggering voltage will be applied between the anode support 102 and the 30 trigger electrode 105. It is however preferable to employ the metal sleeve 107.

In Fig. 2, which shows how the structure is mounted in an envelope, 109 indicates the cathode, 110 the envelope in which the complete 40 structure is mounted, and 111 is the base to which the envelope is secured. 112 and 113 are respectively the terminals to which are secured leads from the trigger electrode 105 and the supporting pillar 102 for the anode 101.

45 According to the present invention, a high electrical stress is produced in the gap between the trigger electrode 105 and the glass bead 106. This is due to the fact that the glass bead has an appreciably higher dielectric constant than that 50 of the air gap, and consequently the voltage drop between the anode and the trigger electrode 105 will be concentrated in the air gap around the trigger electrode 105, causing high electrical stressing in this gap. The purpose of the metal sleeve 107 connected to the anode 101 by the con-

3

ductor 108 is to provide an electrode at anode potential which is closed against the exterior surface of the glass bead 106 and thus obtain the maximum amount of electrical stressing. In cases in which the glass bead 106 is replaced by material having an appreciably higher dielectric constant, it is possible to dispense with the sleeve 107 and rely on the electrode supports 102 to produce the stressing provided these are near the external surface of the bead 106. However, the sleeve 107 gives greater efficiency.

It appears that the electrical stressing produces ionization in the gap around the trigger electrode 105, and that the ions so produced will emerge from the gap and will pass between the 15 sparking tips of the electrodes and this effect will reduce the electrical stress necessary to produce a spark.

What we claim as new and desire to secure by Letters Patent of the United States is:

1. A trippable spark gap device of the kind comprising input and output main electrodes fixed apart appreciably beyond their normal sparkover spacing in relation to a predetermined voltage to be normally applied across the gap, a fixed trigger electrode adjacent one of said main electrodes, an envelope enclosing said electrodes, and at least one inert gas mixed with a small proportion of a quenching gas filling said envelope at a pressure above atmosphere, said trigger electrode being formed with a relatively small radius of curvature at the arcing tip and the main electrode adjacent the trigger electrode being apertured and the tip of the trigger electrode protruding into the neighborhood of the

4

aperture and spaced a predetermined distance from the sides of the aperture such as to ensure a breakdown when a triggering pulse is applied to the trigger electrode, in combination with an insulating tube of appreciable specific inductive capacity and relatively thick wall encircling said trigger electrode over an appreciable portion of its length and internally spaced from said trigger electrode by a relatively small amount to form an annular gap, and an electrical conductor located externally of the insulating tube and electrically connected to said apertured electrode.

5. A trippable spark gap device as defined in claim 1, wherein said electrical conductor comprises an electrical lead to said apertured electrode which is spaced from the exterior of said insulating tube.

10. A trippable spark gap device as defined in claim 1, wherein said external conductor is formed by a metal sleeve closely surrounding said insulating tube.
